UNITED STATES PATENT OFFICE.

CURTIS B. FLORY, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

HYDRAULIC INSTALLATION.

1,358,070.

Specification of Letters Patent. Patented Nov. 9, 1920.

Application filed February 23, 1916. Serial No. 80,515.

To all whom it may concern:

Be it known that I, CURTIS B. FLORY, a citizen of the United States, residing at Wauwatosa, in the county of Milwaukee and State of Wisconsin, have invented a certain new and useful Improvement in Hydraulic Installations, of which the following is a specification.

This invention relates to improvements in the construction of power plants and is especially applicable to hydraulic power installations.

An object of the invention is to provide a pit lining which is of simple and serviceable construction.

It has heretofore been customary in the construction of power plants, and especially in the construction of hydraulic turbine installations, to line the turbine pits with heavily ribbed cast iron rings. In pits of very large diameter the construction of these linings of the prior art is very costly and the cost of transportation of the linings in certain cases is excessive. In order to reduce these costs of construction and transportation, it has been proposed to line turbine pits with steel plates, but this type of lining was not satisfactory for large diameter pits, as heavy and expensive reinforcements were found necessary to make the steel plate linings of sufficient strength.

With the present invention the pit is effectively lined at minimum cost with built-up structural metal, preferably in the form of bars of similar cross section. It is preferred to arrange the bars longitudinally one above the other and to employ flanged bars, the flanges serving as reinforcements and producing a lining which is sufficiently strong to support pits of very large diameter. By employing structural bars of any of the standard cross sections, such as angle bars, channel bars or I-beams, the bars may be shaped and shipped to destination where they may be assembled to form the completed lining. The weight of the lining material as compared with that of a cast lining of equal strength, is considerably decreased, thereby reducing both the cost and difficulties of transportation.

A clear conception of an embodiment of the invention may be had by referring to the drawing accompanying and forming a

part of this specification in which like reference characters designate the same or similar parts.

The single figure of the drawing discloses a transverse vertical section through a hydraulic turbine installation having the invention applied to the pit thereof.

The installation disclosed in the drawing comprises essentially a vertical Francis turbine 1 mounted in a foundation 4 and having a vertical shaft 2 by means of which the turbine is direct connected to the generator 65 3. A pit 9 is formed in the foundation 4 directly above the turbine 1 and permits access to the turbine casing 5, the main stuffing box and the guide vane manipulating mechanism. The turbine 1 receives its actuating fluid from the penstock 7 through a series of movable guide vanes 6 mounted within the casing 5, and exhausts into the usual tail race through a discharge flume 8. The guide vanes 6 are provided with operating stems 10 which are connected in the usual manner with the guide vane actuating mechanisms 11, 12.

The portion of the turbine pit directly adjacent the turbine casing 5, is preferably 80 made circular in form and is lined with a plurality of superposed channel section bars 13. The engaging flanges of adjacent bars 13 are preferably connected by means of rivets or other securing means. The bars 85 13 are preferably formed of mild steel and have their abutting ends connected by means of suitable tie plates 15. As disclosed, the upper portion of the pit 9 is formed of somewhat smaller diameter than 90 the lower portion thereof, thus forming a ledge extending over the lower portion of the pit. The ledge so formed is reinforced by means of a suitable ring 14 formed of an angle bar or a flat plate.

It will be noted that the use of channel section bars 13 to line the pit 9, provides a relatively light, strong and simple lining for the pit. The bars 13 need not necessarily be in one piece, and would preferably 100 be made in several segments in very large installations. These bars need not be of channel section, as angle section bars or I-beams would in some cases be equally as efficient as the channel section bars. While 105 the pit of the disclosure has been illustrated

as being circular, this pit may be of any other form without departing from the scope of the present invention.

It should be understood that it is not desired to be limited to the exact details of construction shown and described, for obvious modifications will occur to a person skilled in the art.

It is claimed and desired to secure by Letters Patent,

1. A pit lining comprising a plurality of longitudinally bent one-piece structural steel bars of standard cross-section having coacting longitudinal flanges extending away from the pit to produce a smooth interior, the opposite ends of each bar being rigidly united.

2. A pit lining comprising a plurality of longitudinally curved one-piece structural steel bars of standard cross-section

having united longitudinal flanges extending away from the pit to produce a smooth interior, the opposite ends of each bar being rigidly united.

3. A pit lining comprising a plurality of one-piece structural steel bars of standard cross-section bent longitudinally and end united to form rings and having coacting longitudinal flanges extending away from the axes of said rings.

4. A lining for vertical pits comprising a plurality of one-piece structural steel bars of channel-section bent and end united to form complete rings and having their flanges united and extending away from the axes of said rings.

In testimony whereof the signature of the inventor is affixed hereto.

CURTIS B. FLORY.
